TRACK CONSTRUCTION

Georg B. Anthonisen, Minneapolis, Minn.

Application July 13, 1935, Serial No. 31,228

22 Claims. (Cl. 238—334)

My invention relates to track construction and has for an object to provide a construction in which greater strength is procured without the use of additional material.

Another object of the invention resides in providing a track construction in which the rails are firmly and securely attached to one another and to the ties on which they are supported.

A still further object of the invention resides in providing a track construction which can be easily installed with a minimum amount of labor.

Another object of the invention resides in the specific construction of the various parts of the invention by means of which the desired results are procured.

An object of the invention resides in providing a tie plate to which the rail may be quickly and easily attached.

A still further object of the invention resides in providing a construction embodying the rail and tie plate, whereby breakage of the flange of the rail where the same rests upon the tie plate is reduced.

An object of the invention resides in providing an angle bar adapted to be increased in strength by virtue of the construction of the rail and tie plate.

Another object of the invention resides in providing a tie plate comprising a body portion on which the rail base rests and having two or more spaced abutments between which the edges of the rail base are disposed.

A feature of the invention resides in spacing said abutments apart a distance greater than the width of the rail base and in providing a key extending between one of said abutments and the juxtaposed edge of the rail base for holding the rail attached to the tie plate.

An object of the invention resides in constructing the face of one or both of the abutments inclined to provide a dovetailed groove adjacent the edge of the rail base and in constructing the key with a dovetailed tongue adapted to enter said groove.

A still further object of the invention resides in constructing the key and the tie plate with juxtaposed parts, one of said parts having a depression therein and the other having a lug preferably in the form of a screw detachably secured thereto and adapted to enter said depression for limiting the movement of the tongue along said groove.

An object of the invention resides in constructing the tongue wedge shaped and in arranging the abutment to form a tapered groove whereby

the key is urged toward the edge of the rails upon movement of the tongue along the groove.

A still further object of the invention resides in providing a spring acting between the key and tie plate, said spring serving to cause movement of the tongue along the inclined face of the abutment for the purpose of urging the key toward the rail base.

Another object of the invention resides in utilizing a compression coil spring and arranging said spring in a manner to encircle the said screw.

An object of the invention resides in constructing the underside of the rail base with a longitudinally extending hollow or concavity and in providing the body of the tie plate on which the rail rests with a protuberance or convex surface fitting into said concavity.

A still further object of the invention resides in the specific construction of the protuberance, whereby stresses on the base of the rail are reduced in such a manner as to prevent breakage of the rail base.

Other objects of the invention reside in the novel combination and arrangement of parts and in the details of construction hereinafter illustrated and/or described.

In the drawings:

Fig. 1 is a plan view of a portion of a track illustrating an embodiment of my invention.

Fig. 2 is a perspective view of the structure shown in Fig. 1 with the splice bars removed.

Fig. 3 is a perspective view of the parts of the tie plate detached from one another.

Fig. 4 is an elevational sectional view taken on line 4—4 of Fig. 1.

Fig. 5 is a transverse sectional view taken on line 5—5 of Fig. 1.

Fig. 6 is a cross sectional detail view of a portion of the structure shown in Fig. 5 and drawn to a larger scale.

Fig. 7 is a cross sectional detail view taken on line 7—7 of Fig. 1.

Fig. 8 is a perspective view of a modification of the tie plate shown in Fig. 3.

Fig. 9 is a plan view similar to Fig. 1 showing still another form of the invention.

Fig. 10 is a perspective view of the structure shown in Fig. 9 with the splice bars removed.

Fig. 11 is a cross sectional detail view taken on line 11—11 of Fig. 10.

Fig. 12 is a plan sectional detail view taken on line 12—12 of Fig. 11.

My improved track construction embodies rails constructed in a particular manner, tie plates applicable thereto and constructed in conformity

therewith, and splice bars or angle bars also constructed in conformity with the particular construction of the rails, all of these parts cooperating to produce an economic track construction of high merit and utility. The various parts of my improved track construction will now be described in detail.

In the drawings, I have shown the ends of two adjoining rails 10 and 10a and the associated structure used in conjunction therewith. Rails 10 and 10a being identical in construction, only rail 10 will be described in detail. The rail 10 is constructed with a head 12 on which the wheels of the rolling stock carried by the track travel 15 and a web 13 connected thereto. The web 13 issues upwardly from a base 14 which is of a suitable width to give the desired strength to the rail. The base 14 is formed upon the underside 15 thereof with a hollow 16 which extends longitudinally 20 throughout the length of the rail and which in the particular embodiment of the invention disclosed, is preferably in the form of a concavity extending from one lateral edge 17 of the base 14 to the other lateral edge 18 thereof. 25 In the drawings, the concavity or hollow 16 is of the full width of the rail, though, if desired, the same may be of lesser lateral extent, providing the same is arranged medially of the lateral edges of the rail base. The base 14 of the rail is preferably first rolled in the customary manner and thereafter bent out of the plane of the bottom thereof to form the concavity 16. In thus rolling the section, pressure is applied to the upper surface of the rail outwardly of a locality indicated 30 by the reference numeral 19 in Fig. 7 leaving a surface 20 on either side of the web 13 of predetermined angularity for a purpose to be presently more fully referred to. The adjoining surfaces 21 have different degrees of angularity or 35 convexity, sloping more abruptly than the surfaces 20. By constructing the rails in this manner the height of the rail is increased without increasing the weight. This increases the moment of inertia of the rail and consequently its 40 strength. The arch action of the base of the rail also enhances its strength.

For the purpose of splicing the adjoining rails 10 and 10a, splice bars or angle bars such as indicated at 22 and 23 in Fig. 5 are used. These 45 bars are constructed with upper and lower ribs 66 and 67 which are formed with beveled surfaces 24 and 25 engaging the heads 12 of the rails upon the under surfaces 26 thereof and the rail base 14 upon the surfaces 20 thereof. Bolts 50 27 passing through said splice bars and the web 13 of the rail hold the parts in proper position. Due to the construction of the base 14 of the rail 10, the rib 67 which extends outwardly from the major portion of the splice bar may be bent 55 downwardly so that the portion 68 of surface 25 which lies outwardly of the line 19 of the surface 20 of the rail base has a greater degree of inclination than the other portion thereof. This increases the moment of inertia of the 60 angle bar without increasing its weight, thereby increasing the strength of the same. It will readily become apparent that the above noted increase in strength of the angle bar, and the consequential increase in the strength of the 65 entire track construction is made possible by the particular construction of the rail base 14.

In the use of my invention, tie plates are preferably used on each tie and particularly under the joints. In the drawings, a tie plate 11 is 70 shown which supports both of the rails 10 and

10a. The particular manner in which the rails cooperate with the tie plate being identical, the following description will refer to rail 10 only. The tie plate 11 comprises a plate-like body portion 28 which is of a suitable length and of a width considerably greater than the width of the rail base 14. This body portion has issuing upwardly from it two spaced abutments 29 and 30 which are disposed a distance apart greater than the width of the rail base 14, and which are disposed inwardly from the lateral edges of the tie plate to provide an intervening portion 31 which is constructed with a bearing surface 32 on which the rail rests and with marginal portions 33 and 34 by means of which the tie plate may 15 be secured to the tie. The under surface 35 of the tie plate is preferably planiform and rests directly upon the tie.

The edge 18 of the rail base 14 is adapted to extend up to a substantially vertical shoulder 36 20 formed on abutment 30 which limits the movement of the said rail laterally in one direction. This abutment is formed with an overhanging flange 37 which overlies the base 14 of the rail 10 and which limits movement of this portion of 25 the base away from the tie plate. In actual use the distance between the flange 37 and the body portion 31 of the tie plate is somewhat greater than the thickness of the rail base 14 at the edge 18 thereof. This leaves a space 38 there- 30 between which permits of a slight movement of the rail base away from the tie plate.

The abutment 29 as previously brought out is spaced from the edge 17 of the rail base 14. The face 39 of this abutment forms another shoulder 35 similar to the shoulder 36 of the abutment 30. This shoulder is beveled, being closest to the rail base at its upper end so as to form a longitudinally extending dovetailed groove 40 in conjunction with the edge 17 of said rail base. Cooperating 40 with this groove is a key 41 which functions in a manner similar to abutment 30 and flange 37 to engage the rail base on the opposite side thereof and to hold the same securely attached to the tie plate. This key may be constructed of a relatively softer material than the tie plate or rail to take up the wear occasioned through lateral strains.

The key 41 includes a longitudinally extending tongue 42 which is dovetailed and of such dimensions as to fit within the dovetailed groove 40. This key is preferably of a length less than the distance between ties or tie plates so that the said key may be readily inserted into the groove 40 and slid longitudinally thereof until the same 55 occupies the position shown in Figs. 1 and 2. The key 41 is constructed with an overhanging flange 43 which overlies the upper surface 21 of the rail base 14 adjacent the edge 17 thereof and which serves a purpose similar to that of the flange 37 60 on abutment 30. This flange in normal position is also slightly spaced from the upper surface 21 of the rail base 14 to permit of slight movement of the said base away from the tie plate thereby preventing excess pumping of the tie. The edge 65 80 of said flange 43 is beveled as shown in Fig. 6 to facilitate removal of the splice bar from the rail joint.

The key 41 is held in position with respect to the tie plate by means of a screw 44. This screw 70 is formed with a wrench head 45 by means of which the same may be rotated and also has a threaded shank 46 adapted to screw into threads 47 formed in the upper portion of the key 41. The extreme end 48 of the shank 46 of screw 44 75

may be turned down to eliminate the threads and serves as a lug for limiting movement of the key with respect to the tie plate. This lug enters a depression or concavity 49 in the abutment 29 and limits the movement of the key 41 with respect to the tie plate. For the purpose of preventing accidental disengagement of the screw 44 from the key 41, a lock washer 50 is placed between the head 45 of said screw and the upper surface of said key. Due to the fact that the abutment 29 is constructed with a dovetailed face, removal of the key through upward movement is prevented and the screw 44 hence serves to hold the key in proper position and to prevent dislocation of the rail from the tie plate.

The tongue 42 of key 41 is constructed with a shoulder 51 which corresponds to the shoulder 36 of abutment 30. This shoulder engages the edge 17 of the rail base 14. Shoulder 51 flares slightly outwardly as shown in Fig. 6 to permit of rocking of the rail on the rail seat. For the purpose of urging the shoulder 51 against the edge 17 of rail base 14, the face 39 of abutment 29 is arranged closer to the shoulder 36 of abutment 30 at one end of the tie plate than the other so that the groove 40 becomes tapered. At the same time the tongue 42 is constructed wedge-shaped so that as the same is moved in the tapered groove 40 the shoulder 51 of key 41 is urged toward the edge 17 of the rail base 14. In order to move the key 41 for an appreciable distance longitudinally to procure wedge action as described, the depression 49 is constructed elongated as best shown in Figs. 1 and 4, whereby sufficient movement may be had to procure the desired frictional results.

In addition to the particular construction of the face 39 of the abutment 29 in the manner shown for the purpose of procuring wedge action, the upper surface 52 of abutment 29 and the portion 69 of surface 32 adjacent abutment 29 are arranged on a slight incline. Cooperating with the surface 52 is a flange 53 formed on key 41. The tongue 42 likewise cooperates with surface 69. The flange 53 and tongue 42 are also arranged in an inclined manner so that as the key travels along the groove 40 the said key is raised upwardly. Upward movement of the key causes the tongue 42 to ride along the beveled face 39 of abutment 29 which in turn crowds the key inwardly, urging the shoulder 51 thereof into engagement with the edge 17 of the rail base 14. It will thus be seen that longitudinal movement of the key in one direction causes the said key to travel inwardly due, first to the disposition of the face 51 of abutment 29 and also due to the sliding movement of the tongue 42 of the key along the face 39 of said abutment by reason of the inclination of the surfaces 52 and 69 of the tie plate.

In order to maintain contact between the key 41 and the edge 17 of the rail 10, I have provided a compression coil spring 54 which encircles the lug 48 formed on the end of the screw 44 and which engages the shoulder 55 formed on said screw at the end of the threads thereof. This spring further seats upon the portion 69 of the upper surface 32 of the body portion 28 of the tie plate and urges the key 41 upwardly, causing the tongue 42 thereof to slide along the beveled face 39 of abutment 29. This spring thus maintains the shoulder 51 at all times in engagement with the edge 17 of the rail base 14.

In the construction of my improved tie plate the rail supporting surface 32 of the body 28 is preferably arranged on a slight incline so that

the flange engaging surface of the rail head bows slightly inwardly to conform to standard rail construction.

The formation of the supporting surface 32 of the tie plate 11 on which the rail base 14 rests is best shown in Fig. 3. This surface has a curved raised portion 56 in the center thereof, and an adjoining surface indicated by the reference numeral 57. The raised portion 56 of the supporting surface 32 constitutes a protuberance which in the form of the invention shown in Fig. 3, is circular in form, being preferably in the shape of a segment of a large sphere. The protuberance 56 is so constructed that the center portion thereof instead of being spherical has a cylindrical portion 60 between the two lines 58 and 59 indicated in Fig. 3. The curvature of the surfaces 56 and 60 is preferably the same as the curvature of the concavity or hollow 16 of the rail base 14. The rail hence engages the surface 32 for a portion of the width of the cylindrical surface 60 thereof and is free from the protuberance outwardly therefrom. The surface 57 of the body portion 28 outwardly of the protuberance 56 is cylindrical in form and the axis of the same is transverse to the rail so that the said surface recedes from the surface 56 at the corners of the bearing surface 32 of the tie plate. It will thus be seen that at such corners, relief is provided so that the base 14 of the rail is free from the same. The concave construction of the rail and the complementary surface of the tie plate serve to restrain lateral movement of the rails with respect to the tie plate, thereby decreasing the wear on the keys. At the same time, breakage of the rail flange when the rail is subjected to lateral forces is greatly reduced. Due to the formation of the rail the movement of inertia of the rail is increased, producing a corresponding increase in strength without increase in weight.

For the purpose of attaching the tie plate to a tie the marginal portions 33 and 34 of the body portion 28 of the tie plate are constructed with rectangular holes 61 extending therethrough, through which suitable rail spikes 62 may be driven into the tie proper.

The manner of using my invention is as follows: After the ties have been laid the tie plates are applied to the ties and positioned thereon by means of a suitable rail gauge. The tie plates are then attached to the ties by means of the rail spikes 62 which are driven through the holes 61 formed in the marginal portions 33 and 34 of the body portion 28 of the tie plates and into the ties. After the tie plates are in position, the rails are placed thereon and the bases thereof moved under the flanges 37 of the tie plates and until the edges 18 of said rails engage the shoulders 36 of the tie plates. Keys 41 are now applied by inserting the tongues 42 thereof into the grooves 40 and the said keys driven in until the shoulders 51 thereof engage the opposite edges 17 of the rail bases. Springs 54 are next inserted through the threaded openings in the keys 41 and the screws 44 applied. When these screws enter the depressions 49 the keys are held in position and the rails become attached to the tie plates.

My invention in addition to holding the rails in position, prevents creepage of the rails relative to the ties. Toward this end the tie plates are preferably alternately arranged in reversed manner on the various ties so that the keys are inserted from opposite ends of the tie plates on alternate ties. Due to the tapering of the beveled face of the abutments of the tie plates, the

keys are caused to travel along the dovetailed grooves when there is any creepage of the rails. This causes wedge action, clamping the edges of the rail base securely between the shoulders of the tie plates which has the effect of restraining longitudinal movement of the rails. By reversing alternate tie plates, resistance to movement of the rails in either direction can be procured. It will thus be seen that the invention not only serves to hold the rails attached to the ties, but also serves to prevent creepage of the rails longitudinally with respect to the ties.

In Fig. 8 I have shown a slight modification of the invention in which the supporting or bearing surface of the tie plate is constructed somewhat differently than that shown in Fig. 3. The supporting surface there illustrated is designated by the reference numeral 63 and is cylindrical in form having its axis situated longitudinally. The curvature of this surface is preferably the same as the curvature of the concavity or hollow 16 of the rail base 14. The corners 64 of the surface 63 are cut down so as to afford relief from pressure against the rail base at such localities. This serves the same purpose as the portion 57 of surface 32 in the other form of the invention.

In Figs. 9, 10, 11 and 12 I have shown another form of my invention. In these views the rails are designated by the numerals 110 and 110a and the tie plate which cooperates with the rails by the numeral 111. These parts will now be described in detail.

The rail 110 is constructed with a head 112 on which the wheels of the rolling stock carried by the track travel and a web 113 connected thereto. The web 113 issues upwardly from a base 114 which is of a suitable width to give the desired support to the rail. The undersurface 115 of the base 114 has a concavity 116 throughout the central area thereof and is flat in proximity to the lateral edges 117 and 118 thereof. The upper surfaces 120 and 121 of the base 114 are constructed similar to the rail 10.

The tie plate 111 comprises a plate-like body portion 128 which is of a suitable length and of a width considerably greater than the width of the rail base 114. This body portion has issuing upwardly from it two spaced abutments 129 and 130 which are disposed a distance apart greater than the width of the rail base 114, and which are disposed inwardly from the lateral edges of the tie plate to provide an intervening portion 131 which is constructed with a bearing surface 132 on which the rail rests and with marginal portions 133 and 134 by means of which the tie plate may be secured to the tie. The under surface 135 of the tie plate may be constructed either as shown in Fig. 3 or Fig. 8, the form illustrated being similar to that shown in Fig. 8, except that the curved protuberance 169 thereof is narrower to fit the concavity 115.

The edge 118 of the rail base 114 is adapted to extend up to a substantially vertical shoulder 136 formed on abutment 130 which limits the movement of the said rail laterally in one direction. This abutment is formed with an overhanging flange 137 which overlies the base 114 of the rail 110 and which restrains movement of this portion of the base away from the tie plate. In actual use the distance between the flange 137 and the body portion 131 of the tie plate is somewhat greater than the thickness of the rail base 114 at the edge 118 thereof. This provides clearance between the flange 137 and said base

114 permitting a slight relative movement between rail base and tie plate and preventing excess pumping of the ties.

The abutment 129 as previously brought out is spaced from the edge 117 of the rail base 114. The face 139 of this abutment forms another shoulder similar to the shoulder 136 of abutment 130. This shoulder is beveled, being closest to the rail base at its upper end so as to form a longitudinally extending dovetailed groove 140 in conjunction with the edge 117 of said rail base. Cooperating with this groove is a key 141 which functions in a manner similar to abutment 130 and flange 137 to engage the rail base on the opposite side thereof and to hold the same securely attached to the tie plate. This key may be constructed of a relatively softer material than the tie plate or rail to take up the wear occasioned through lateral strains.

The key 141 includes a longitudinally extending tongue 142 which is dovetailed and of such dimensions as to fit within the dovetailed groove 140. This key is preferably of a length less than the distance between ties or tie plates so that the said key may be readily inserted into the groove 140 and slid longitudinally thereof until the same occupies the position shown in Figs. 9 and 10. The key 141 is constructed with an overhanging flange 143 which overlies the upper surface 121 of the rail base 114 adjacent the edge 117 thereof and which serves a purpose similar to that of the flange 137 on abutment 130. This flange in normal position is also slightly spaced from the upper surface 121 of the rail base 114 to permit of slight movement of the said base 35 away from the tie plate. The tongue 142 of key 141 is constructed with a shoulder 151 which corresponds to the shoulder 136 of abutment 130. This shoulder engages the edge 117 of rail base 114, and is constructed arcuate as best shown in Fig. 9 so as to engage the edge of the rail at one locality intermediate the ends of the tie plate. This feature of the invention compensates for irregularities in construction of the tie plate and rail and concentrates the pressure on the rail at a predetermined locality.

The key 141 is held in position with respect to the tie plate by means of a screw 144. This screw is formed with a wrench head 145 by means of which the same may be rotated and also has a threaded shank 146 adapted to screw into threads 147 formed in the upper portion of the key 141. The intermediate portion 216 of the shank 146 of screw 144 is turned down to eliminate the threads and the extreme end 148 of said shank is further reduced in diameter to form a shoulder 149 adjacent the intermediate portion 216. The reduced end 148 of screw 144 serves as a lug for limiting movement of the key with respect to the tie plate. This lug enters a transverse slot 149 in the body portion 131 which is of a width substantially equal to the diameter of the lug 148 and of a length greater than the diameter of said lug so as to permit transverse movement of the key 141 with respect to the rail 110. The shoulder 149 seats against the upper surface 132 of the body portion 131 of the plate 111 and as the screw is rotated causes the key 141 to travel upwardly. Upward movement of the key causes the tongue 142 of said key to travel upwardly along the beveled face 139 of abutment 129, which urges the shoulder 151 into engagement with the edge 117 of the rail base 114. The screw 144 may travel laterally by reason of the slot 149 to accommodate movement of the key toward the rail. A 75

notch 120 in abutment 129 receives the intermediate portion 216 of screw 144, when the key is in its farthermost position with respect to the edge 117 of rail base 114.

5 Encircling the shank 146 of screw 144 and seated against the head 145 of said screw and the flange 143 of key 141, is a compression coil spring 150. This spring serves to prevent accidental rotation of the screw 144 and holds the parts in 10 adjusted position.

For the purpose of attaching the tie plate to a tie the marginal portions 133 and 134 of the body portion 128 of the tie plate are constructed with rectangular holes 161 extending therewith through which suitable rail spikes 162 may be driven into the tie proper.

The manner of using my invention is as follows: After the ties have been laid the tie plates are applied to the ties and positioned thereon by 20 means of a suitable rail gauge. The tie plates are then attached to the ties by means of rail spikes 162 which are driven through the holes 161 formed in the marginal portions 133 and 134 of the body portion 128 of the tie plate and into the ties. After the tie plates are in position, the rails are placed thereon and the bases thereof moved under the flanges 137 of the tie plates and until the edges 118 of said rails engage the shoulders 136 of the tie plate. Keys 141 are now applied by 30 inserting the tongues 142 thereof into the grooves thereof and said tongues slid along the grooves until the threaded openings in said keys register with the slots 149. Screws 144 with springs 150 encircling the shanks thereof are next screwed 35 into the threads 147 until the lugs 148 enter the slots 149, and shoulders 119 seat against the surfaces 132 of the tie plates. As the screws are further screwed into the keys the said keys raise and slide along the beveled faces 131 of abutments 129. This crowds the shoulders 151 of the 40 keys against the edge 117 of the rail base and clamps the rail securely in position.

My invention is highly advantageous in that an 45 extremely simple and practical construction is provided whereby rails may be properly supported and attached to the ties and to one another. Tie plates constructed in accordance with my invention may be produced at an economical cost. The attachment of the rails to the tie plates is 50 exceedingly simple and can be procured in a minimum length of time. With my invention, less parts are required than with other similar tie plates now in common use for the purpose. With my invention breakage of the rail base is greatly 55 reduced and the rail caused to properly seat upon the tie plate. My improved tie plate is considerably lighter in weight than the tie plates now used and in addition is fully as strong. There are no fragile parts to break or get out of order with 60 my invention and where wear occurs, shims may be readily applied to take up the wear. With my invention the greater part of the wear occurs on the keys when the keys are constructed of a softer material and when wear becomes excessive, new 65 keys may be substituted without requiring complete new tie plates. Both the rail and splice bars are strengthened by means of the construction used with my invention.

Changes in the specific form of my invention, 70 as herein disclosed, may be made within the scope of what is claimed without departing from the spirit of my invention.

Having described my invention, what I claim as new and desire to protect by Letters Patent is:

75 1. A tie plate for application to the base of a

7 rail comprising a body portion on which the rail rests, two parallel abutments extending upwardly therefrom and between which the base of the rail is disposed, one of said abutments being spaced from the juxtaposed edge of the rail base 5 and being constructed with an inclined face to form a dovetailed groove therebetween, a key having a dovetailed tongue adapted to be inserted into said groove said face having sufficient angularity and said key being of suitable width to restrain removal of the key upwardly, a depression in said tie plate and a lug attachable to said key and adapted to enter said depression, said lug limiting the movement of said tongue relative to said groove.

15 2. A tie plate for application to the base of a rail comprising a body portion on which the rail rests, two parallel abutments extending upwardly therefrom and between which the base of the rail is disposed, one of said abutments being 20 spaced from the juxtaposed edge of the rail base and being constructed with an inclined face to form a dovetailed groove therebetween, a key having a dovetailed tongue adapted to be inserted into said groove said face having sufficient angularity and said key being of suitable width to restrain removal of the key upwardly, a depression in said tie plate and a screw threaded into 25 said key and having a lug thereon adapted to enter said depression, said lug limiting the movement of said tongue relative to said groove.

3. A tie plate for application to the base of a rail comprising a body portion on which the rail rests, two parallel abutments extending upwardly therefrom and between which the base of the rail is disposed, one of said abutments being 35 spaced from the juxtaposed edge of the rail base and being constructed with an inclined face to form a dovetailed groove therebetween, a key having a dovetailed tongue adapted to be inserted 40 into said groove said face having sufficient angularity and said key being of suitable width to restrain removal of the key upwardly, said key and tie plate having juxtaposed parts, one of said parts being formed with a depression and the 45 other of said parts having a lug detachably secured thereto and entering said depression, said lug restraining longitudinal movement of said tongue relative to said groove.

4. A tie plate for application to the base of a 50 rail comprising a body portion on which the rail rests, abutments extending upwardly therefrom and between which the base of the rail is disposed, one of said abutments being spaced from the juxtaposed edge of the rail base and being 55 constructed with an inclined face to form a dovetailed groove therebetween, a key having a dovetailed tongue adapted to be inserted into said groove, means for limiting the movement of said tongue within said groove, and resilient means 60 acting between the tie plate and key for causing the tongue to slide along said inclined face and toward the edge of the rail base.

5. A tie plate for application to the base of a 65 rail comprising a body portion on which the rail rests, abutments extending upwardly therefrom and between which the base of the rail is disposed, one of said abutments being spaced from the juxtaposed edge of the rail base and being 70 constructed with an inclined face to form a dovetailed groove therebetween, a key having a dovetailed tongue adapted to be inserted into said groove, said key and tie plate having juxtaposed parts, one of said parts being formed with a depression and the other of said parts having a 75

- screw threaded therein and entering said depression and a compression coil spring encircling said screw and acting between said key and tie plate for causing movement of said tongue along said 5 inclined face and toward the edge of said rail base.
6. A tie plate for application to the base of a rail comprising a body portion on which the rail rests, abutments extending upwardly therefrom 10 and between which the base of the rail is disposed, one of said abutments being spaced from the juxtaposed edge of the rail base and being constructed with an inclined face to form a dovetailed groove therebetween, a key having a dovetailed 15 tongue adapted to be inserted into said groove, said tie plate having a transverse slot therein, a screw threaded into said key and having a lug entering said slot, said slot guiding said key for movement toward and from the rail base and an 20 abutting surface formed on the screw for engaging the tie plate, said surface operating to raise the key upon rotation of the screw in one direction to cause the key to travel along the inclined face and to be urged against the rail base.
- 25 7. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and formed with an arcuate shoulder for 30 engagement with the adjoining edge of the rail, and means for urging said key upwardly to cause the same to ride along said inclined face and to force said shoulder against the edge of the rail.
- 35 8. A tie plate for application to the base of a rail comprising a body portion on which the rail rests, two parallel abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and limiting lateral movement of the rail 40 relative to the tie plate, and restraining means attached to the key and engaging the tie plate for restraining longitudinal movement of the key relative to the tie plate.
- 45 9. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said key and tie plate having juxtaposed parts, one of said parts having a transversely extending shoulder and the other having a lug detachably secured thereto and slidably engaging said shoulder, said lug restraining longitudinal movement 50 of said key relative to said groove.
- 55 10. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed 60 tongue adapted to be inserted into said groove, a shoulder formed on said tie plate and a lug detachably secured to said key for slidably engaging said shoulder, said lug restraining longitudinal movement of the key relative to said groove. 5
- 65 11. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said tie plate having a transverse slot therein and a lug on said key extending into said slot and restraining longitudinal movement of the key relative to the groove, said lug being slidable transversely and vertically in said slot. 10
- 70 12. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said tie plate and key having juxtaposed parts formed with facing depressions and a resilient member disposed within both of said depressions and urging said key to move vertically relative to said tie plate. 15
- 75 13. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and a resilient member acting between said key and tie plate, said resilient member holding said key in position and urging said key to move vertically relative to said tie plate. 20
- 80 14. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and a reciprocal member attached to said key and having a free end adapted to engage said depression for restraining longitudinal movement of the key relative to the groove. 25
- 85 15. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said tie plate having a depression therein, and a reciprocal member attached to said key and having a free end adapted to engage said depression for restraining longitudinal movement of the key relative to the groove. 30
- 90 16. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and means urging said key upwardly and against said inclined face to force the key toward the rail base. 35
- 95 17. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, and a resilient member holding said key in position and urging said key to move vertically relative to said tie plate. 40

and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, the juxtaposed abutment having a longitudinally extending groove therein extending through the inclined face thereof, and means carried by said key for engagement with said groove to limit the movement of the key relative to the tie plate.

17. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said tie plate having a transverse slot therein, a screw threaded into said key and having a lug entering said slot, said slot guiding said key for movement toward and from the rail base.

18. In combination, a support for a member having lateral surfaces, said support having a surface, abutments extending outwardly from said surface of the support, said member being disposed between said abutments with its lateral surfaces facing said abutments, one of said abutments being spaced from the corresponding lateral surface of the member and being constructed with an inclined face to form a dovetailed groove therebetween, a key having a dovetailed tongue adapted to be inserted into said groove, said key approaching said last referred to surface of the member upon movement away from the surface of the support, and means acting between the support and key for urging the key away from the surface of the support.

19. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dove-

tailed groove therebetween, a key having a dovetailed tongue adapted to be inserted into said groove, the juxtaposed abutment having a depression therein opening toward said rail, and means carried by said key for engagement with said depression for limiting the movement of the key relative to said plate, said means urging the key to travel along said dovetailed groove and away from the tie plate.

20. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said key being narrower at both ends and being formed with a shoulder extending intermediate its ends for engagement with the edge of the rail.

21. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, a flange on said tongue overlying said abutment and means extending through said flange and engaging the tie plate for urging the tongue away from the tie plate.

22. A tie plate for application to the base of a rail comprising a body portion on which the rail rests, abutments extending upwardly therefrom and between which the base of the rail is disposed, one of said abutments being spaced from the juxtaposed edge of the rail base and being constructed with an inclined face to form a dovetailed groove therebetween, a key having a dovetailed tongue adapted to be inserted into said groove, said groove extending below the under surface of the rail base, and means for urging the key to travel along said dovetailed groove and away from the bottom of the same.

GEORG B. ANTHONISEN.
